Primary Examiner — T. Chase Nelson*Assistant Examiner* — Jonathan J Han(74) *Attorney, Agent, or Firm* — Finch & Maloney PLLC(57) **CLAIM**

The ornamental design for a hand guard for a submachine gun, as shown and described.

DESCRIPTION

FIG. 1 is a left elevation view of a hand guard for a submachine gun showing the design;

FIG. 2 is a right elevation view thereof;

FIG. 3 is a rear elevation view thereof;

FIG. 4 is a front elevation view thereof;

FIG. 5 is a top plan view thereof;

FIG. 6 is a bottom plan view thereof; and,

FIG. 7 is a rear perspective view thereof.

Broken lines in the drawings are for the purpose of illustrating environmental structure and form no part of the claimed design.

The break lines in the drawings indicate that any portion of the article between the break lines shown forms no part of the claimed design.
